(**) Term: **15 Years**

(57) **CLAIM**

(21) Appl. No.: **29/636,262**

The ornamental design for an enclosure for an electronic device, as shown and described.

(22) Filed: **Feb. 7, 2018**

DESCRIPTION

(51) LOC (11) Cl. **14-02**

FIG. 1 is a perspective view of an enclosure for an electronic device in accordance with one embodiment of the invention;

(52) U.S. Cl.

FIG. 2 is a front view of the enclosure of FIG. 1;

USPC **D14/440**

FIG. 3 is a rear view of the enclosure of FIG. 1;

(58) **Field of Classification Search**

FIG. 4 is a left view of the enclosure of FIG. 1;

USPC D14/440; 206/45.23, 320, 45.2;

FIG. 5 is a right view of the enclosure of FIG. 1;

361/679.55; 294/25; 224/218; 235/441

FIG. 6 is a top view of the enclosure of FIG. 1; and

CPC ... G06F 1/1628; G06F 1/1626; A47B 23/044;

FIG. 7 is a bottom view of the enclosure of FIG. 1.

H04B 1/3888; H05K 5/0217

FIG. 8 is a perspective view of an enclosure for an electronic device, in accordance with a second embodiment of the invention;

See application file for complete search history.

FIG. 9 is a front view of the enclosure of FIG. 8;

(56) **References Cited**

FIG. 10 is a rear view of the enclosure of FIG. 8;

U.S. PATENT DOCUMENTS

FIG. 11 is a left view of the enclosure of FIG. 8;

1,347,839 A 7/1920 Coons et al.

FIG. 12 is a right view of the enclosure of FIG. 8;

1,659,395 A 2/1928 Douglas et al.

FIG. 13 is a top view of the enclosure of FIG. 8; and

4,544,123 A 10/1985 Peacock

FIG. 14 is a bottom view of the enclosure of FIG. 8.

5,029,784 A 7/1991 Blahout

FIG. 15 is a perspective view of an enclosure for an electronic device, in accordance with a third embodiment of the invention;

5,377,794 A 1/1995 Book

FIG. 16 is a front view of the enclosure of FIG. 15;

5,439,101 A 8/1995 Brink et al.

FIG. 17 is a rear view of the enclosure of FIG. 15;

5,445,251 A 8/1995 Redwood

FIG. 18 is a left view of the enclosure of FIG. 15;

5,607,054 A 3/1997 Hollingsworth

FIG. 19 is a right view of the enclosure of FIG. 15;

5,717,566 A 2/1998 Tao

FIG. 20 is a top view of the enclosure of FIG. 15; and,

5,877,896 A 3/1999 Gremban

FIG. 21 is a bottom view of the enclosure of FIG. 15.

5,887,723 A 3/1999 Myles et al.
